DESIGN FOR AN INJECTION MACHINE

Walter Ernst and Johan A. Muller, Mount Gilead, Ohio, assignors to The Hydraulic Development Corporation, Inc., Wilmington, Del., a corporation of Delaware

Application July 3, 1939, Serial No. 85,838

Term of patent 3½ years

To all whom it may concern:

Be it known that we, Walter Ernst and Johan A. Muller, citizens of the United States, residing at Mount Gilead, in the county of Morrow and State of Ohio, have invented a new, original, and ornamental Design for an Injection Machine, of which the following is a specification, reference being had to the accompanying drawings forming a part thereof.

In the drawings:

Figure 1 is a plan view of our injection machine showing our new design;

Figure 2 is a front elevation thereof;
Figure 3 is a rear elevation thereof;
Figure 4 is a left-hand end elevation thereof;
and

Figure 5 is a right-hand end elevation thereof.
We claim:

The ornamental design for an injection machine, substantially as shown.

WALTER ERNST.
JOHAN A. MULLER.
